(57) **CLAIM**

The ornamental design for a cable storage container, as shown and described.

DESCRIPTION

FIG. 1 is a front elevational reference view of the cable storage container in a state of use;

FIG. 2 is another front elevational reference view thereof showing a state of use;

FIG. 3 is a front, right-side, top perspective view thereof;

FIG. 4 is a front elevational view thereof;

FIG. 5 is a rear elevational view thereof;

FIG. 6 is a top plan view thereof, the bottom plan view (not provided) being a minor image thereof; and,

FIG. 7 is a right-side elevational view thereof, the left-side elevational view (not provided) being a mirror image thereof.

The broken lines in the drawings illustrate environment and parts of the cable storage container that form no part of the claimed design.
